UNITED STATES PATENT OFFICE.

SAMUEL HAYWARD, OF BOSTON, MASSACHUSETTS.

FURNITURE.

SPECIFICATION forming part of Letters Patent No. 363,389, dated May 24, 1887.

Application filed February 26, 1887. Serial No. 222,936. (No model.)

To all whom it may concern:

Be it known that I, SAMUEL HAYWARD, of Boston, in the county of Suffolk and State of Massachusetts, have invented certain new and useful Improvements in Furniture, of which the following, taken in connection with the accompanying drawings, is a specification.

My present invention relates to devices for raising and lowering articles of furniture to adapt them to different uses or more desirable positions, and is an improvement upon the invention described in the Letters Patent No. 356,938, granted to me February 1, 1887, and is especially adapted to use upon easy-chairs for varying the height and inclination of the seat and adjusting the angle of the back.

The object of my invention is to simplify the means for changing the angle of the supporting-legs of any article of adjustable furniture for the purpose of varying the height of the same, and in the case of adjustable chairs to vary the inclination of the chair-back and the spread of the legs from front to rear by the same operation that changes the height of the seat, whereby a chair having a back adjustable to different angles may be rendered more stable than those now in use without having so broad a base when the back is in its most upright position as to be objectionable; and it consists in certain novel features of construction and combination of parts, which will be readily understood by reference to the description of the drawings, and to the claims, to be hereinafter given.

Of the drawings, Figure 1 represents a central vertical sectional elevation of a chair embodying my invention. Fig. 2 represents an inverted sectional plan of the same, the cutting plane being on line *xx* on Fig. 3; and Fig. 3 represents a partial sectional elevation through one of the side frames of the chair, showing the mechanism for operating the legs and back.

In the drawings, *A A* are the side frames, connected together by the seat portion *B* and the rounds *C C*, and each of which is provided with a suitable arm, *D*, and two legs, *E E*, a portion, *a*, of each of which is thinner than the remaining portion, and freely moves about the round *C*, within the slot *A'* of the side frame.

The portion *a* of each leg extends some dis-

tance from the fulcrum *C*, and to its end is connected a link, *F* or *F'*, the opposite ends of which are pivoted to the nut *G*, mounted and movable upon the vertical screw *H*, which has secured to its upper end the pinion *I*, by which it is revolved in its bearings. The nut *G* fills the slot *A'*, so that it cannot turn upon said screw *H*, but must be moved lengthwise thereof as said screw is revolved. The pinions *I* are adapted to be revolved by the large gear-wheel *J*, which is mounted upon the bar *K*, secured to the under side of the seat-frame *B*, and which is provided upon its under side with bevel gear-teeth which mesh into and have motion imparted thereto by the bevel-pinion *L*, which is secured to a short shaft mounted in the stand *M*, and to the opposite end of which is secured the hand-wheel *N*, by which said pinion may be turned to impart motion to the gear-wheel *J*.

The hand-wheel *N* may be dispensed with and a crank used without altering the principles of my invention.

The lower ends of the side frames *O* of the back portion are made of such a thickness as to allow said ends to be freely moved within the slot *A'* about the fulcrum-pin *b*, by which said back is secured to the main side frames *A A*. The extreme lower ends of said frames *O O* are connected by the links *P* to the upwardly-projecting arms of the rear legs, *E*, all as shown in Fig. 3.

The links *F'*, which connect the rear legs with the nuts *G*, are considerably shorter than the links *F*, which connect the forward legs to said nuts, so that when said nuts are moved the length of said screws *H* the rear legs will be moved a greater distance about their fulcrums than will the forward legs, which will cause the seat portion to be inclined slightly to the rear; or, in other words, the back of the seat will be lower than the front portion.

The side frames *O O* of the back are connected together by the wooden bars *c* and *d*, and the whole chair is provided with suitable cushions, which may be of any form, and attached in any well-known manner.

The operation of the chair is as follows: All the parts being in the positions shown in Fig. 1, (in which case the nut *G* will be at the upper end of the screw *H*, and the legs and back in the nearest to a vertical or upright position

they can assume, as shown in dotted lines in Fig. 3,) and the occupant of the chair desiring the back to be inclined to a greater or less degree, he has only to turn the hand-wheel N, 5 which, by means of the pinion L and gear J, will impart motion to the pinions I I and revolve the screws H H, to which said pinions are secured. The rotation of said screws will force the nuts G G, mounted thereon, down- 10 ward, thereby operating the legs E, so that the lower ends will be swung outward and assume positions much farther apart, the bases or ends of the rear legs moving much farther to the rear than do the bases of the forward legs 15 move to the front. This action allows the seat to drop a short distance, with its back or rear end the lowest, as shown in Fig. 3, and while in this position, with its back tilted to the rear, which is done simultaneously with the movement of the legs, it is more capable of resisting any tendency of overturning.

If desired, the pinion L and hand-wheel N may be dispensed with, and the wheel J may be turned by the operator seizing the rim or 25 spokes of the same.

When applied to an article of furniture which it is desired to raise and lower bodily, and at the same time maintain the same in a level position, or at the same angle at all points 30 of elevation, the links F and F' are to be made of the same length, as shown and described in the Letters Patent hereinbefore referred to.

What I claim as new, and desire to secure by Letters Patent of the United States, is—

35 1. In an article of furniture, the combination of the main body of the article, four independently pivoted legs, vertical screws mounted in bearings in said main body, a pinion secured to each of said screws, a gear-wheel engaging with each of said pinions, a non-revolving nut mounted upon each of said screws, and a series of links connecting the upper ends of the pivoted legs to said nuts.

2. A chair provided with a series of pivoted legs and an independently pivoted back, all 45 connected together and arranged to be simultaneously moved about their pivots to vary the distance between the feet at the same time that the inclination of the back is changed.

3. A chair provided with a series of pivoted 50 legs and an independently pivoted back, all connected together, and constructed, arranged, and adapted to be simultaneously moved about their pivots a different distance, the rear pair of legs moving about their fulcrums a greater 55 distance than the forward legs.

4. A chair provided with hollow or slotted side frames, in combination with a screw mounted in bearings in the slotted portion of each of said side frames, a nut movable lengthwise upon said screw, a pinion secured to said screw, a gear-wheel for imparting motion to said pinions, a series of pivoted legs, links for connecting said legs to said nuts, a pivoted back, and links for connecting said back with 60 the rear pair of legs.

5. The combination of the hollow or slotted side frames, a screw mounted in suitable bearings in the slotted portion of each of said side frames, a nut movable lengthwise upon said 70 screw, a gear-wheel for imparting motion to said pinions, a series of pivoted legs, a link for connecting the forward leg to said nut, a shorter link for connecting the rear leg to said nut, a pivoted back, and links for connecting 75 said back with the rear pair of legs.

In testimony whereof I have signed my name to this specification, in the presence of two subscribing witnesses, on this 24th day of February, A. D. 1887.

SAMUEL HAYWARD.
